Attorney.

UNITED STATES PATENT OFFICE.

GEORGE F. HUTCHINS, OF WORCESTER, MASSACHUSETTS, ASSIGNOR TO CROMPTON & KNOWLES LOOM WORKS, A CORPORATION OF MASSACHUSETTS.

TUFT-YARN CARRIER.

1,065,871.

Specification of Letters Patent. Patented June 24, 1913.

Application filed March 14, 1912. Serial No. 683,811.

To all whom it may concern:

Be it known that I, GEORGE F. HUTCHINS, a citizen of the United States, residing at Worcester, in the county of Worcester and State of Massachusetts, have invented certain new and useful Improvements in Tuft-Yarn Carriers, of which the following is a specification.

My invention relates to tuft yarn carriers for Axminster looms, and particularly to tuft yarn carriers for wide looms, having center bearings for the contiguous journals of the tuft yarn spools, where two or more spools are used on one carrier, and my invention particularly relates to the center bearings for the spools.

The tuft yarn carriers of the class referred to having spools attached thereto are carried in a chain, which chain has a rotary movement, ordinarily in a substantially vertical plane, and the tuft yarn carriers, and the spools attached thereto, are at predetermined times removed from said chain and carried down to insert the tuft yarns into the fabric, in the usual and well known way. In the rotary movement of the chain, carrying the tuft yarn carriers, and the spools attached thereto, the spools at certain times occupy a position, in which the bearings for the ends of the spools are below the spool, or in a plane underneath the spool, so that in case of movable or pivotally mounted bearings for the ends of the spool, it is necessary to so construct the movable part of the bearing that it will be held in proper position and locked to the stationary part of the bearing, no matter in what position the tuft yarn carrier and the spool or spools thereon may be, otherwise when the spools are in a reverse position, and below the tuft yarn carriers, the movable portion of the bearing would become detached from the stationary part, and allow the end of the spool to drop out of the bearing.

The object of my invention is to improve upon the ordinary construction of the center bearing for the contiguous ends of the tuft yarn spools, and more particularly to provide a fixed rigid bearing portion, and a movable or pivotally mounted bearing portion, said movable bearing portion provided with a pivotally mounted spring actuated locking latch or lever, the actuating spring acting to hold said pivotally mounted lever

in operative position, to lock the pivotally mounted bearing portion to the stationary bearing portion, no matter in what position the spool may be, all as will be hereinafter fully described.

I have shown in the drawing a detached portion of a spool frame for a tuft yarn carrier, and a spool, with my improvements in center bearings combined therewith.

Referring to the drawing:—Figure 1 is a front view of the spools, and part of a spool frame, with my improvements, combined therewith. Fig. 2 is a section, on line 2, 2, Fig. 1, looking in the direction of arrow *a*, same figure; the broken lines show the movable bearing in its open position. Fig. 3 is a plan view of the center bearing, shown in Fig. 2, detached, and looking in the direction of arrow *b*, same figure. Fig. 4 shows a modified construction of some of the parts of the center bearing shown in Fig. 2. Fig. 5 is an edge view of the parts shown in Fig. 4, looking in the direction of arrow *c*, same figure.

In the accompanying drawing, 1 is a bar, having secured thereon the metal plate 2, which carries the tubes 3, through which the tuft yarns pass from the two spools 4; the spool at the right is only partially shown. Each spool 4 has a longitudinally extending groove 4' therein, to receive a wire rod, not shown, to hold the ends of the tuft yarns, not shown, on winding the spools. In the drawing, I have shown in this instance one spool, and the end of a second contiguous spool, which spools extend the width of the loom. The spools 4 have beam heads 5 thereon, in this instance made of pressed sheet metal.

6 is the end journal, and 7, see Fig. 2, is the center journal, comprising an enlarged head with a fin or extension 7' thereon, adapted to enter a corresponding shaped recess in the journal, not shown, on the contiguous end of the adjoining spool, to form a coupling or connection between the two contiguous spools.

All of the above mentioned parts may be of any usual and well known construction.

I will now describe my improvements, which, as above stated, relate particularly to the center bearing for the spools.

The center bearing for the inner contiguous spool journals consists of the stand 8,

which has a foot portion 8', which may be secured to the cross bar 1 by a screw, not shown, extending through a hole 8" in the foot 8'. The stand 8 extends upwardly, and 5 has the recessed portion 8^a at its upper end, forming one-half of the journal bearing, and the top portion 8^b with a beveled edge. The other half of the bearing consists of the movable cap 9, which is pivotally attached 10 at its lower end by a pin 9' to the stand 8, to have a pivotal or swinging motion thereon. The cap 9 has in this instance the extension 9" thereon, which extends over the upper end of the stand 8, and also the extension 9''' thereon, which in this instance has an opening 9'''' therethrough, see Fig. 1, to receive the end of a latch 10, which is pivotally connected with the extension 9''' by a pin 11. The latch 10 has the downwardly 20 extending engaging end 10', which in this instance extends through an open end slot in the extension 9'', and is made hook or beveled shaped at its lower end, to extend over the beveled end 8^b on the upper part 25 of the stand 8, see Fig. 2. The latch 10 has the extension 10'', forming a handle portion to be engaged by the operator.

A helically coiled expansion spring 12 extends between the handle portion 10'' of 30 the latch 10, and the upper part of the extension 9''' on the cap 9, and acts to yieldingly hold the latch 10 in its closed position, as shown in Fig. 2. To disengage the latch 10, the engaging end 10'' is pressed inwardly, against the action of the spring 12, to disengage the hooked end of the latch from the beveled end 8^b on the stand 8, and then the cap 9 is moved outwardly, as indicated by broken lines in Fig. 2, to allow of 40 the free removal of the journals on the contiguous ends of the spools from the center bearing.

In Figs. 4 and 5 is shown a modified construction of the movable cap 9. In said 45 figure, the latch 10, pivoted on the cap 9, is done away with, and the latch lever 13 is substituted. The latch lever 13 is pivotally mounted at its lower end on a pin 14, on a lug 15 on the stand 8. A helically coiled expansion spring 16 extends between the lower 50 end of the lever 13 and the edge of the stand 8, and acts to yieldingly move inwardly the upper end of the lever 13. The upper end of the lever 13 extends in an open end slot on 55 the upper end of the stand 8, and also in an open end slot on the extension 9'' on the cap 9, and has the side extensions 13' thereon, which extend over the sides of the slotted part on the extension 9'', as shown in Fig. 5, 60 when the lever 13 is in its inward position as shown in Fig. 4, to secure the cap 9 to the stationary part of the bearing. When it is desired to move the cap 9 away from the stationary part of the bearing, the lever 13 65 is moved outwardly at its upper end, as indi-

cated by broken lines in Fig. 4, to allow the cap 9 to be swung or moved on its hinged joint, as indicated by broken lines in Fig. 4.

The advantages of my improvements will be readily appreciated by those skilled in the art; they are of very simple construction, and the operator can easily disconnect the movable part of the bearing from the stationary part, to allow the removal of the inner journals of the spools from the bearing, and the spring actuated latch, which locks the movable part of the bearing to the stationary part, will be operative to hold the movable part of the bearing in proper position, relative to the stationary part, 75 when the spool is in a reverse position, which would not be the case if a weighted latch was used, as the weight on the latch would act to open it, or move it into non-locking position, when the spool was in a reverse 80 position, that is with the locking latch on the underside of the spool.

It will be understood that the details of construction of my improvements may be varied if desired.

Having thus described my invention, what I claim as new and desire to secure by Letters Patent is:

1. In a tuft yarn carrier for Axminster looms, etc., a bearing for the contiguous 95 journals of two spools, comprising a stationary part, and a movable part, and a pivotally mounted spring actuated lever or latch having a handle portion, for locking the movable part to the stationary part, the 100 actuating spring acting to hold the movable part locked to the stationary part in whatever position the spools may be.

2. In a tuft yarn carrier for Axminster looms, etc., a bearing for the contiguous 105 journals of two spools, comprising a stationary part, and a movable part, pivotally mounted on said stationary part, and a pivotally mounted spring actuated lever or latch having a handle portion, for locking 110 the movable part to the stationary part.

3. In a tuft yarn carrier for Axminster looms, etc., a bearing for the contiguous 115 journals of two spools, comprising a stationary part, and a movable part, pivotally mounted on said stationary part, and a pivotally mounted spring actuated lever or latch having a handle portion, pivotally mounted on said movable part, to lock the movable part to the stationary part.

4. In a bearing for the contiguous journals on two spools, the combination with a stand having a recessed portion, of a movable cap, pivotally mounted on said stand, and having a recessed portion, and a pivotally mounted spring actuated lever or latch, for locking said movable cap to said stand.

5. In a bearing for the contiguous journals on two spools, the combination with a 130

stand having a recessed portion and a flattened upper end, of a movable cap, pivotally mounted on said stand, and having a recessed portion and an extension to extend over the upper end of said stand, and a pivotally mounted spring actuated lever or latch, for locking said movable cap to said stand.

6. In a bearing for the contiguous journals on two spools, the combination with a stand having a recessed portion, and a flattened upper end, of a movable cap, pivotally

mounted on said stand, and having a recessed portion, and an extension to extend over the upper end of said stand, and a spring 15 actuated lever or latch, pivotally mounted on said cap, and engaging the flattened end on said stand, to lock said movable cap to said stand.

GEORGE F. HUTCHINS.
